BY ATTORNEY

UNITED STATES PATENT OFFICE

2,468,217

ELECTRICAL HEATING UNIT

John Maller, Aberdeen, Wash.

Application May 13, 1948, Serial No. 26,892

7 Claims. (Cl. 219—39)

1

This invention relates to improvements in electrical heating units and is particularly adapted to fireplaces.

My new and improved electric heating unit is adapted to be installed within fireplaces, or it may be installed in homes without a fireplace but having a recess within the wall of the building for receiving the same.

In the case of installing my fireplace in buildings where no previous fireplace existed a trim may be placed around my unit representing a fireplace, although I do not wish to be limited to any particular method of installing the same within the building, as the objects of my invention may be carried out in various types of installation.

The primary object of my invention is to circulate air into and through my new and improved electric heating unit. This air coming in the bottom of the unit entering a preheated chamber, in which is installed an air circulator, the air then being delivered out through this preheated chamber into the surrounding area.

A further object of my invention is the provision of a special preheating chamber which absorbs heat from an electrical heating element after which the heat is distributed by a forced air stream to the areas to be heated.

A still further object of my invention is the providing of an electrical heating unit that will circulate the air in the space to be heated.

Another object of my invention is the controlling of the heating elements independently of the air circulating unit so that these elements may be either on or off while the air is in motion.

These and other incidental objects will be apparent in the drawings, specification and claims.

Referring to the drawings:

Figure 1 is a front view of my new and improved electric heating unit installed within a conventional fireplace.

Figure 2 is a sectional view taken on the line 2—2 of Figure 1 through the electrical heating unit, the surrounding fireplace being indicated by broken lines.

Figure 3 is a sectional plan view of my new and improved electrical heating unit taken on line 3—3 of Figure 2, particularly illustrating the wiring, the damper control and the relative position of the various elements.

Figure 4 is a side view of my new and improved electrical heating unit.

Referring more specifically to the drawings:

My new and improved electric heating unit is indicated in general by numeral 1, installed in

2

a fireplace 2, referring to Figure 1, the said fireplace being indicated by broken lines in Figure 2 for convenience of illustration.

My electric heating unit consists of a sheet metal housing or casing 3, open at its front 4 and having a trim flange 5 associated therewith. This housing consists of two parts, the forward chamber 6 and the rear chamber 7 divided by the partitions or wall 8, best illustrated in Figures 2 and 3. The lower edge of the wall 8 terminates in a sub-base 9 spaced away from the bottom 10 of the unit as by the passageway 11. The passageway 11 has a grille 12 located at its forward end parallel to the front 4 of the electric unit facing the interior of the room to be heated.

The rear end 13 of the passageway communicates with the lower part of the chamber 7. The chamber 7 is heated by the electric elements 14 through the partition or wall 8 which transfers the heat from the element into the heat receiving and dissipating material 15. The material 15 consists preferably of sheet rock which has the ability to absorb heat from the partition or plate 8 dissipating the same into the chamber 7.

I have provided a fan 16 for circulating air from the room to be heated through the grille 12, passageway 11 up through the heated chamber 7 and out the adjustable dampers 17 and the grilles 18, best illustrated in Figures 1 and 2. The dampers 17 consist of cross slats 19 which are secured to the shafts 20, which are rotatably mounted within the unit 1 at 21 and 22, referring to Figure 3. These shafts are connected together by arms 23 and links 24 so that they will work together.

An arm 25 is secured to one of the shafts 20 and to the control rod 26. By operating the control rod 26 manually the shutters 19 can be opened or closed depending upon the amount of air desired to be allowed to pass through the damper 17. The grilles 18 allow air to pass through picking up heated air being directly radiated from the heating element 14.

I have provided an ornamental grille 27 for hiding the heat elements 14 from view. The rear of this grille may consist of a reflecting material so that additional heat may be reflected back through the partition or plate 8, which in turn will be absorbed by the sheet rock 14 and dissipated into the air stream within the chamber 7.

The electric motor fan unit 16 receives its electrical energy through the wiring 28 and switch controls 29 and 30 from the main supply line 31. The heating element 14 also receives its electrical

energy from the line 31 through the switch control box 30.

I will now describe the operation of my new and improved electric heating unit adapted to be used in connection with fireplaces and the like. In the event it is desired to heat the room the switches 29 and 30 are turned on. This supplies electric energy to the heating element 14. We will assume from the switch 30, which may be of a type for various degrees of heat. We will also assume that when this switch was turned on the circulating fan 16 is brought into action.

The electric heating element will then heat the partition 8 transferring the said heat into the said rock material 15 and as fresh air is pulled through the grille 12 through the passageway 11 up into the chamber 7 by the electric fan 16 this air will be heated by the heat dissipated from the sheet rock material 15. This air will then be forced out through the damper 17 and the grilles 18 into the room to be heated. There will of course be a certain amount of heat picked up from the outer edges of the heating element 14, but it is one of the objects of my invention not to pass an air stream through the heating element directly; as by doing so considerable heating efficiency is lost.

The principle feature of my invention is the radiation of heat from the heating element 14 through the wall 8 and into the sheet rock 15, which then is picked up by the air stream. By this method I achieve considerable efficiency which cannot be done by circulating air through the heating unit itself.

As stated above the rear of the ornamental grille 21 may act as a reflector directing the heat from the heating element more completely through the rear wall 8 of the unit and into the sheet rock insulating sheet 15. When it is desired to circulate air alone the switch 30 may be turned off and the switch 29 employed to operate the circulating fan only.

While I have shown my heating unit adapted to fit into a fireplace, I do not wish to be limited to this particular adaptation of my invention, as my unit can be installed in a portable cabinet in which case the unit itself consisting of the housing 3 and the chamber 7 may be insulated on the outside thereof so as to conserve the heat developed therein. In my drawings I have not illustrated the same insulated, as the fireplace itself provides a good insulator, although the same could have an insulation sheet completely therearound. Access to the circulating fan 16 may be had through the door 32 communicating with the chamber 7.

What I claim is:

1. An electric heater, comprising a casing having an open front, a partition dividing said casing into front and rear compartments the rear side of said partition having a covering of heat absorbing and dispensing material, an opening in the top of said partition for communication between said compartments, an electric heating element in said front compartment adjacent said partition for radiating heat to said partition, and means in said rear compartment for directing air upwardly along said partition to be heated and pass outwardly through the opening in said partition into said front compartment and out through the open front thereof.

2. A heater as defined in claim 1, wherein a reflecting screen is positioned in front of said heating element to reflect heat back to said partition.

3. A heater as defined in claim 2, wherein a horizontal partition separates said front compartment from the bottom of said casing to form a passageway from the front of said casing to the rear compartment for supplying air thereto.

4. A heater as defined in claim 3, wherein said casing is formed to fit in a fireplace and has a laterally extending flange at the sides and top for overlying the front wall of the fireplace.

5. A heater as defined in claim 4, wherein said vertical partition has openings in the side portions thereof to pass air outwardly from said rear compartment past the sides of the heating element.

6. A heater as defined in claim 5, wherein dampers are rotatably supported at said vertical partition to control the top opening and have levers connected thereto, and a control rod is connected to said levers and extends through said flange on one side of said casing for the selective control of said dampers.

7. A heater as defined in claim 6, wherein said rear compartment air directing means comprises an electrically driven fan, and switches are mounted in said flange on one side of said casing for controlling said fan and said heating element respectively.

JOHN MALLER.
